UNITED STATES PATENT OFFICE.

ALVIN M. WILLIAMS, OF WEST ORANGE, NEW JERSEY.

PYROGRAPHIC BURNER.

No. 870,754.

Specification of Letters Patent.

Patented Nov. 12, 1907.

Application filed March 30, 1907. Serial No. 365,568.

To all whom it may concern:

Be it known that I, ALVIN M. WILLIAMS, a citizen of the United States, residing at West Orange, in the county of Essex and State of New Jersey, have invented a new and useful Improvement in Pyrographic Burners, of which the following is a specification.

This invention relates more especially to the fastening of the shell or burner-tube to the lug or shank of the burner, and the objects of the invention are to secure such an attachment which shall be simple and inexpensive to manufacture; to provide a fastening which shall at the same time be secure and not liable to be loosened by the expansion and contraction of its parts under the heat of the burner, and to obtain other advantages and results which may be brought out in the following description.

Referring to the accompanying drawings, in which like numerals of reference indicate corresponding parts in each of the several figures, Figure 1 is a side elevation of a pyrographic burner of my improved construction; Fig. 2 is a longitudinal central section of the burner with the shell forced into place on the lug, the band being not yet in its final position; and Fig. 3 is a longitudinal central section of the burner complete.

25 In said drawings, 1 indicates the tubular shank or lug, adapted at one end, as at 2, to be screwed into a handle (not shown), as is common in the art.

The shell or burner-tube 3 is preferably of platinum with its outer end 4 shaped or formed in any suitable manner for accomplishing the pyrographic work to be done, and in its side is the usual vent 5. The end of the lug which is to receive the said shell is exteriorly reduced as at 6, said reduced portion being preferably slightly tapered as shown, and forming where it joins 35 the body of the lug an abrupt shoulder 7. This re-

duced portion 6 of the lug is adapted to telescopically enter the shell 3 and is made of such size that the said shell must be forced on by a considerable pressure, so that a tight fit or union is secured. The ductility of the shell enables it to stretch slightly when forced on, 40 and the shoulder 7 provides a limiting stop for the end edges of the shell. A band 8 is then forced down over the shell 3 on the reduced portion 6 of the lug, until it also engages the shoulder 7, as shown in Figs. 1 and 3, said band thus tightly and permanently binding the 45 shell 3 to the lug 1. Preferably the band 8 is of such thickness that when in final position its outer surface will be flush with the outer surface of the adjacent portion of the lug and form a smooth continuation thereof.

50 The tubular passage of the lug is denoted by the reference numeral 9, a reduced tip 10 being inserted in the forward end of the lug to project into the shell, as is common. A spirally coiled wire 11 upon the forward end of the tip serves to diffuse the gas, as usual.

55 It will be noted that by my improved construction the inner surface of the band 8, for its entire length bears on nothing but the shell, whereby said band can be forced into a most intimate binding relation to the shell and reduced end portion of the lug.

60 Having thus described the invention, what I claim as new is:

In a pyrographic burner, the combination of a lug having a reduced end, a shell telescopically receiving said reduced end, and a band separate and independent of the lug 65 arranged on said reduced end and adapted to bear for the whole length of its inner surface only on the said shell.

ALVIN M. WILLIAMS.
